UNITED STATES PATENT OFFICE

PERCY B. CAMP, OF MAYWOOD, ILLINOIS, ASSIGNOR TO UNIVERSAL DRAFT GEAR ATTACHMENT CO., A CORPORATION OF ILLINOIS

SLACK ADJUSTER

Application filed November 28, 1930. Serial No. 498,653.

This invention relates to railway brakes and more particularly to slack adjusters therefor.

One of the objects of the invention is the provision of new and improved means for automatically taking up the slack in the brake operating mechanism for railway trains.

Another object of the invention is the provision of new and improved means for locking the parts in brake operating positions when the device is not functioning as a slack adjuster.

A further object of the invention is the provision of new and improved slack adjusting devices that may be mounted on and movable with portions of the brake operating mechanism, and that is so constructed that the use of the device will not in any way interfere with the normal operation of the brake operating mechanism.

A still further object of the invention is the provision of a slack adjuster that is simple in construction, inexpensive to manufacture, automatic in action, efficient in operation, and that is not likely to become broken or get out of order.

Other and further objects and advantages of the invention will appear from the following description taken in connection with the accompanying drawings, in which

Fig. 1 is a plan view of the slack adjusting mechanism;

Fig. 2 is a section on line 2—2 of Fig. 1;

Fig. 3 is a side elevation of the device, with parts in section and parts broken away, showing the adjusting mechanism in position for taking up the slack;

Fig. 4 is a view similar to Fig. 3, but showing the device at the completion of its slack adjusting movement;

Fig. 5 is a section on line 5—5 of Fig. 4;

Fig. 6 is a side elevation of the device, the view being taken from the opposite side from that shown in Fig. 4;

Fig. 7 is a section on line 7—7 of Fig. 4;

Fig. 8 is a section on line 8—8 of Fig. 4;

Fig. 9 is a diagrammatic view of the brake operating mechanism as applied to the trucks of a railway car;

Fig. 10 is a perspective view of the attach-

ing member or housing with parts broken away;

Fig. 11 is a perspective view of the adjusting mechanism; and

Fig. 12 is a perspective view of the holding or retaining member.

Referring now to Fig. 9 of the drawing, the reference characters 10 indicate railway trucks having the wheels 11, and the brakes therefor comprising the live and dead brake levers 12 and 13 respectively, brake shoes 14 and 15 operated by said levers, connecting bar 16, brake rod 17, the live and dead cylinder levers 18 and 19, the cylinder lever connection 21 and the brake cylinder 22, as is usual in such constructions.

In the construction and operation of railway brakes, the parts are so constructed and arranged that the operating piston of the air cylinder will have a predetermined travel, usually about 8". As the shoes become worn, this distance will increase unless provision be made for taking up the slack, and since the levers are so arranged as to transmit their maximum power at the limit of travel of the piston when the shoes are first applied, it follows that the efficiency of the brake is greatly reduced when the shoes become worn, unless means are provided for maintaining the parts in a predetermined relation.

The present invention seeks to provide means for automatically taking up the slack during the operation of the brakes, for compensating for the wear of the brake shoes. It is also desirable that this mechanism be so constructed that it may be attached to the moving parts of the brake operating mechanism and will not interfere with the normal operation of this mechanism.

In the form of construction shown, which is by way of example only, the slack adjuster is designated generally by the reference character 23 and is shown as being applied to both the live and dead cylinder levers 18 and 19, see Fig. 9. It is understood, however, that it may be applied to other parts of the moving mechanism if so desired.

The adjuster comprises an attaching member or anchor member 24 which may be in the form of a housing having the upper wall

25, side walls 26 and 27 respectively, and a ledge 28 on its lower portion. The side wall 27 is provided with a slot 29 through which the attaching lever may extend as will presently appear. The housing 24 is provided with a pair of attaching plates 31 having an opening 32 therethrough for connecting the housing to the brake rod 17, see Fig. 9.

The under side of the upper wall 25 is provided with one or more racks having ratchet teeth 33 extending longitudinally of the housing. As shown, the wall 25 is provided with integral rack teeth at each side thereof. A holding or retaining member designated generally by the reference character 34 is slidably mounted within the housing and is provided with one or more teeth 35 for engaging the teeth 33 of said housing. Preferably a plurality of teeth 35 are employed, arranged in sets at opposite sides of an opening 36 extending through said retaining member. The two sets of teeth 35 are adapted to engage the two sets of teeth 33 on the wall 25 as shown in Figs. 4 and 5 of the drawings.

25 The holding member 34 is provided with an angular slot 37, the rear portion of the slot being substantially horizontal for receiving one end of the cylinder lever 18 which also extends through the slot 29 in the attaching or holding member 24. The rear portion of the slot extends downwardly and outwardly for receiving the pivot pin of the adjusting device as will presently appear. A pin 38, see Fig. 2, extends through the aligned openings 36 in the holding member 34 for pivotally connecting the cylinder lever 18 to said holding member 34.

Suitable means are provided for advancing the housing 24 relative to the holding member 20 step by step for compensating for the wear in the brake shoes, that is, for taking up the slack in the brake operating mechanism, caused by the wearing of the brake shoes.

As shown, adjusting mechanism designated generally by the reference character 39 is employed for this purpose. This mechanism comprises a lever 41 having a detent 42 slidably mounted in one end thereof and its opposite end provided with a spring seat 43. The 45 detent 42 is normally held in extended position by a spring 44 housed within said detent and the upper end of said lever. The lever is pivotally mounted in any suitable manner in the depending portion of the slot 37 of the holding member 34. As shown, the member 34 is bifurcated at what for convenience of description will be termed its rear end, thereby providing a slot 45 through which the upper end of the lever 41 is adapted to extend. 50 By means of this arrangement the adjusting mechanism will function without undue friction since the friction due to its operation will be equalized on the two sides of the adjusting lever.

The lever 41 is provided with a trunnion

or pivot pin 46 for engaging the rear depending portion of the slot 37. In the form of construction shown, which is by way of example only, the pin or trunnion 46 is separate from the lever 41. It is provided with an angular portion 40 which engages a corresponding angular opening in said lever. The end of the pin is provided with a collar 50, see Fig. 11, for constituting a journal of the same diameter as the inner portion of the trunnion 46.

The retaining member 34 is provided with a spring seat 47 on its lower portion which is arranged opposite the spring seat 43 when the parts are assembled. A spring 48 having its ends engaging in the seats 43 and 47 is adapted to normally hold the lower end of the lever 41 in forward position.

Mounted on or secured to one end of the pivot pin 46 is an arm 49 having a contact member 51 pivotally mounted on its outer end. The position of the contact member 51 may be adjusted by means of a set screw 52 as clearly shown in Figs. 6 and 11 of the drawings. A stop 53 is mounted on any convenient portion of the car for engaging the contact member 51 when the slack in the brake operating mechanism exceeds a predetermined maximum, during the operation of the brake. This stop is so mounted that when the brake operating mechanism is properly adjusted it will not be operated by the stop 53, when the brakes are applied.

As the brake shoes wear or as the slack accumulates in the brake operating mechanism, the levers 18 and 19 will tend to move beyond their normal position in applying the brakes, and this in turn will cause the contact member 51 to engage the stop and move the lever 41 forwardly, thereby compressing the spring 48.

The detent 42 which is carried by the lever 41 will tend to ride forwardly over the teeth, and when the slack is such that the forward movement of the housing 24 is equivalent to the distance between two of the notches, the detent will ride over the adjacent tooth, and when the brakes are released the spring 48 will expand and move the housing 24 forwardly, causing the teeth 33 to ride forwardly one notch over the teeth 35 of the holding member 34. The parts are so constructed that the detent 42 will be advanced one or more teeth for each reciprocation of the arm 49 for taking up slack in excess of the predetermined maximum.

In applying new brake shoes it is necessary to adjust the holding mechanism to provide sufficient clearance for the new shoes, and in doing so a considerable amount of excessive slack in the brake operating mechanism frequently results. It is therefore desirable that the contact member be so constructed that it will take up the slack and at the same time

will not interfere with the normal application of the brakes.

In the present construction, when the brakes are applied with excessive slack in the brake operating mechanism the lever arm 39 and contact arm 51 will rotate to a position to pass beneath the contact member to permit sufficient movement of the lever 18 to apply the brakes, and when the brakes are released 10 the contact arm will move about its pivot and permit the lever to return to its normal inoperative position.

This operation will take up a portion of the slack and the succeeding applications of 15 the brakes will take up the additional slack in the mechanism. This is considered an important feature of the invention since the workman who changes the brake shoes need not be particular about the amount of slack 20 he provides so long as sufficient slack is provided to apply the shoes.

Suitable means are provided for preventing 25 accidental disengagement of the teeth 33 and 35, when the adjusting mechanism is not being operated. Any suitable mechanism 30 may be provided for this purpose. As shown, the forward portion of the retaining member 34 is provided with a pivoted dog 54 which in normal position is adapted to engage the ledge 28, see Fig. 7, for preventing the housing 24 from rising relative to the holding member 34 whereby the teeth 33 and 35 will be maintained in engagement. Any appropriate means may be provided for moving the dog 54 to inoperative position to permit the housing 24 to advance relative to the holding member 34.

In the form of construction shown, the dog 40 54 is provided with a rearwardly extending arm or finger 55 which is adapted to be engaged by a finger 56 for rotating the dog 54 to the position shown in Fig. 8 when the lever 41 is operated, thereby permitting the teeth 33 on the housing 25 to ride over the teeth 35 45 on the retaining member 34. When the brake is released, the lever 41 will be returned to normal position by the spring 48, permitting the dog 54 to fall by gravity into position above the ledge 28.

50 The operation of the device may be briefly summarized as follows: When the brakes are applied in the usual manner, the ends of the levers to which the slack adjuster 23 is attached will be moved toward the stop members 53, see Figs. 1, 2 and 3, and the contact member 51 will be so adjusted by the set screw 52 that it will engage or be closely adjacent to the stop when the brakes are applied before slack develops in the operating mechanism.

As the shoes wear, causing a gradually increasing slack in the operating mechanism, the levers 18 and 19 will move farther and farther toward the stops 53, thereby causing the arms 49 to rotate the levers 41 more and more against the compression of the springs

48 until, after repeated operations of the brake, the slack becomes sufficient to permit the detent 42 to be advanced to the next adjacent tooth, and in the meantime the finger 56 on the lever 41 will engage the member 55 70 and turn the dog 54 out of engagement with the ledge 28 whereupon when the brake is again released the spring 48 will return the lever 41 to normal position and advance the housing 24 to take up the slack to compensate 75 for the wear of the brake shoes and other parts of the mechanism.

The release of the lever 41 will release the dog 54 which in turn will fall by gravity 80 against the edge of the ledge 28 and when the housing is lowered after its teeth 33 ride over the teeth 35 on the holding member 34 it will fall in position above the ledge 28 for preventing accidental disengagement of the teeth 33 and 35.

While two of the slack adjusters 23 are employed and are shown as being attached to the cylinder levers, one to the fulcrum end of one lever and the other to the end opposite the fulcrum of another lever, it is understood 90 that only one need be employed and that it may be used on any suitable moving portion of the brake operating mechanism.

The attaching member 24 is preferably in the form of a housing in order to protect the operating mechanism, but it is understood that it may be otherwise.

When it is desired to adjust the attaching member relative to the holding member for providing excess slack for any reason as for applying new brake shoes, the dog 54 is disengaged in any suitable manner as by the finger and the attaching member 24 elevated to disengage its teeth from the teeth 35 and then moved along the holding member until the desired slack is provided.

It is thought from the foregoing, taken in connection with the accompanying drawings, that the construction and operation of my device will be apparent to those skilled in the art, and that various changes in size, shape, proportion and details of construction may be made without departing from the spirit and scope of the appended claims.

I claim as my invention:

1. In brake operating mechanism including a brake rod and a lever for operating same, a slack adjusting device connected to said rod and lever and movable therewith, said device comprising a housing, a rack associated therewith, a holding member cooperating with said rack, adjusting mechanism comprising a stop and a pivoted arm for engaging said stop for effecting the movement of said adjusting mechanism and for operating the same to advance said rack relative to said holding member during the operation of said brake operating mechanism for taking up the slack therein, said arm being adapted to pass by said stop when the

slack in the brake operating mechanism is beyond a predetermined maximum.

2. In combination, a brake operating mechanism comprising a system of levers and brake rods for operating the brakes, a housing connected to one of said rods, a rack in said housing, a holding member connected to one of said levers and having a tooth for engaging said rack, an adjusting device pivoted to said holding member and having a spring-pressed detent for engaging said rack, a stop, an arm for engaging said stop for advancing said detent along said rack upon the operation of said mechanism for taking up the slack therein, and resilient means for returning said adjusting device to normal position for advancing said rack upon the release of the brakes.

3. In combination, a brake operating mechanism comprising a system of movable levers and brake rods for operating the brakes, a holding member connected to one of said levers, an attaching member movably mounted relative to said holding member and adjustable along the same, means operated by the operation of said mechanism for advancing said rack along the holding member for taking up the slack in said mechanism, and means for preventing accidental displacement of said attaching member along said holding member when said device is not operating, to take up slack in said mechanism, said first named means comprising a stop and a contact member movable into engagement with said stop when the slack in said brake operating mechanism exceeds a predetermined maximum and movable past said stop when said slack exceeds a predetermined amount.

4. In a slack adjuster for railway brakes, a housing having two parallel sets of teeth extending longitudinally thereof, a holding member on which said housing slidably mounted and having two sets of teeth for engaging the teeth on said housing, said housing being provided with means for attaching the same to a brake rod and said holding member being adapted to be attached to a brake operating lever, a lever pivoted in said holding member and having a spring-pressed detent for engaging the teeth on the housing, a spring for normally holding said lever in inoperative position, having a relatively fixed stop, an arm on said lever for engaging said stop for moving said lever for advancing the detent over the teeth on said housing during the application of the brakes whereby on release of the brakes the housing will be advanced for taking up the slack in the brake operating mechanism.

5. In a slack adjuster, an attaching member provided with a plurality of teeth extending longitudinally of said member, means for attaching said member to a movable element of a brake operating mechanism, a holding

member movable relative to said attaching member and provided with one or more teeth for engaging the first-named teeth, said movable member being adapted to be connected to another movable element of the brake operating mechanism, slack adjusting mechanism including a stop, a pivoted arm for engaging said stop, a movable member having means for engaging the teeth on said attaching member for advancing the same upon the operation of the brakes for taking up slack in the brake operating mechanism.

6. In a brake operating mechanism comprising movable members for applying the brakes, a slack adjuster device comprising an attaching member connected to certain of said movable members, and means including a holding member adjustable relative to said attaching member, and adjusting mechanism for operating said device upon the operation of said brake operating mechanism for taking up the slack therein, said adjusting mechanism comprising a stop, a lever arm, a movable member for engaging said stop for operating said adjusting mechanism when the slack in said brake operating mechanism exceeds a predetermined maximum amount and for moving past said stop when said slack exceeds a predetermined amount.

7. In a brake operating mechanism comprising levers and cooperating brake rods, a slack adjusting device connected to the end of one of said levers opposite the fulcrum, and means including a stop, a lever arm and a movable member on said arm for engaging said stop for operating said device upon the operation of said mechanism for taking up the slack in said mechanism.

8. In a slack adjuster for brake operating mechanism, a holding member, an attaching member adjustable along said holding member, adjusting mechanism for moving said attaching member step by step along said holding member, said mechanism comprising a pawl, a stop, an arm for operating said pawl, and movable means carried by said arm for engaging said stop when the slack in the brake operating mechanism exceeds a predetermined maximum for advancing said holding member one step along said attaching member for each operation of the brake and for moving past said stop when the slack exceeds a predetermined amount.

9. In a slack adjuster for brake operating mechanism, an attaching member for attachment to a brake rod, teeth on said member, a holding member for attachment to a brake lever, teeth on said holding member for engaging the teeth on the attaching member, adjusting mechanism for advancing said attaching member along said holding member, said adjusting mechanism comprising an oscillating arm, a pawl for engaging the teeth of said attaching member for advancing said attaching member one or more teeth for each oscillation of said arm, a stop, and a pivoted

contact member on said arm for engaging said stop for oscillating said arm.

10. In a slack adjuster for brake operating mechanism, an attaching member having teeth longitudinally thereof, a holding member having teeth for engaging said first-named teeth, adjusting mechanism comprising a spring-pressed arm, a spring-pressed pawl for engaging the teeth on said attaching

10 member, said pawl being adapted to be moved along said attaching member by said arm for advancing the attaching member one step for each oscillation of said arm when the slack in said brake operating mechanism exceeds a predetermined maximum and movable means on said arm for engaging a stop for oscillating said arm.

11. In a slack adjuster for brake operating mechanism, an attaching member having a rack extending longitudinally thereof, a holding member having teeth cooperating with the teeth of said attaching member for holding the parts in adjusted position, an arm, a spring engaging said arm, a pawl movable with said arm, a stop, a contact member movably mounted on said arm and adapted to engage said stop for moving said arm for storing energy in said spring and for advancing said pawl along said rack during the application of the brakes when the slack in the brake operating mechanism exceeds a predetermined amount, said contact member being movable past said stop in both directions.

12. In a slack adjuster for brake operating mechanism, an attaching member adapted to be connected to a brake rod, a holding member adjustable along said attaching member and adapted to be connected to a brake lever, interengaging teeth fixed to said members, means for advancing said attaching member one or more steps during the application and release of said mechanism when the slack in said mechanism exceeds a predetermined amount, and means whereby said brakes may be applied irrespective of the amount of slack in said mechanism.

13. In a slack adjuster for brake operating mechanism, an attaching member adapted to be connected to a brake rod, a holding member adjustable through said attaching member and adapted to be connected to a brake lever, interengaging teeth fixed to said members, means for advancing said attaching member one or more steps during the application and release of said mechanism when the slack in said mechanism exceeds a predetermined amount, and means for preventing the disengagement of said teeth except when said first-named means is operated.

14. In combination, brake operating mechanism comprising a system of movable levers and brake rods for operating the brakes, slack adjusting means associated with said system for taking up excessive slack therein, said

means comprising a stop, a rack, a detent for engaging said rack and means for engaging said stop for advancing said detent along the teeth of said rack when the slack in said system exceeds a predetermined maximum, said means being movable past said stop in a reverse direction without affecting said detent.

15. In combination, brake operating mechanism comprising a system of movable levers and rods for operating the brakes, a slack adjusting device associated with a movable member of said system for taking up excess slack in said system, said device comprising holding and adjusting means, a stop and means for engaging said stop for advancing said means along said movable member for taking up the slack in said system when the same exceeds a predetermined maximum and for moving past said stop when the slack exceeds a predetermined amount, said last named means being movable past said stop in a reverse direction without affecting the adjustment of said first named means.

16. A slack adjuster for use on brake operating mechanism, comprising holding means adapted to be connected to a movable portion of said mechanism, attaching means adapted to be connected to another portion of said mechanism and adjustable along said holding means for taking up slack in said mechanism and adjusting mechanism adapted to automatically adjust one of said means relative to the other during the application and release of the brakes when the slack in said brake operating mechanism exceeds a predetermined amount, said mechanism comprising a movable member adapted to engage a relatively fixed member for operating said adjusting mechanism when moved in one direction and adapted to be moved past said relatively fixed member in the opposite direction without affecting said mechanism.

17. In combination, brake operating mechanism comprising a system of movable levers and brake rods for operating the brakes of a vehicle, a relatively fixed member, a slack adjusting device interposed in said mechanism for taking up the slack therein and comprising a movable member for engaging said relatively fixed member for operating said device during the operation of the brakes when the slack in said mechanism exceeds a predetermined amount, said movable member being movable past said fixed member in a reverse direction without operating said device.

18. In brake mechanism of the class described, the combination therewith of a slack adjuster adapted to connect two adjacent moving parts of the mechanism, said adjuster comprising an attaching member adapted to be affixed to one part, a holding member adapted to be affixed to the other part, ratchet teeth cooperating to hold the attaching and

holding members against relative movement in one direction, an actuating mechanism including a contact member adapted to advance a detent along the ratchet teeth when excess brake travel exists, and spring means for moving the holding member relative to the attaching member upon release of the brakes after the detent has been advanced along the teeth, and a dog adapted to positively lock the attaching and holding members in adjustment when the brakes are in normal release position.

In testimony whereof I affix my signature.

PERCY B. CAMP.
